(57) **CLAIM**

The ornamental design for a printer, as shown and described.

DESCRIPTION

FIG. 1 is a front, top, and right side perspective view of a printer showing our new design in a closed position; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a perspective view of the printer in an open position; and,

FIG. 9 is a front view of the printer in a closed position in a use state.

The broken lines immediately adjacent the shaded areas depict the bounds of the claimed design, while all other broken lines are directed to environment.

In addition, the unshaded surfaces directly adjoining the solid line edges form no part of the claimed design.

The broken lines form no part of the claimed design.
